UNITED STATES PATENT OFFICE.

WILLIAM H. WOOD, OF ROCHESTER, NEW YORK.

BUTTON SHOE.

SPECIFICATION forming part of Letters Patent No. 369,087, dated August 30, 1887.

Application filed April 13, 1887. Serial No. 234,610. (No model.)

To all whom it may concern:

Be it known that I, WILLIAM H. WOOD, of Rochester, in the county of Monroe and State of New York, have invented a certain new and useful Improvement in Shoes; and I do hereby declare that the following is a full, clear, and exact description of the same, reference being had to the drawings accompanying this application.

10 My improvement relates to button shoes, and more particularly to the fly or overlapping part that connects with the buttons. In common shoes of this kind the button-holes of the fly are exposed and open their whole 15 length, and when the shoe has been used a considerable time these button-holes wear and present an unsightly appearance and gape open, showing the stocking beneath.

It is the object of my improvement to obviate 20 these difficulties; and my invention consists in the combination, with the button-fly, of an overlying piece of leather which laps over the inner ends of the button-holes, covering a portion of their length, all as hereinafter 25 described.

In the drawings, Figure 1 is a side elevation of a shoe, showing my improvement. Fig. 2 is an enlarged face view of a portion of the button-fly and the overlying strip. Fig. 3 is an 30 enlarged cross-section of the meeting edges of the shoe through one of the button-holes.

A indicates the shoe, and B the button-fly, the latter being scalloped in the usual way, or plain, as desired.

35 a a are the button-holes in the fly, of usual form, and b b are the buttons.

My improvement is as follows:

C is an overlying piece of leather attached to the outside of the fly in any suitable manner, its lower edge resting some distance back from the edge of the fly and overlapping and covering a portion of the length of the button-

holes—one-half, more or less, as shown. The strip is stitched intermediate the button-holes, forming pockets or gussets d d, which are the 45 parts resting directly over the button-holes, and which are loose, forming simply covers. In the drawings these pockets are of V form, but, if desired, may be segmental, square, or of any desired shape.

50 The advantages of this device are that it gives additional strength to the shoe; it covers and shields the inner ends of the button-holes, saving the necessity of finishing them up so elaborately as is now done; also, and which is of 55 much importance, it covers the unsightly opening and spreading of the inner end of the button-holes, and the consequent exposure of the stocking, that occur in common shoes. When made in ornamental form, it adds to the beauty 6c of the shoe.

Having described my invention, what I claim as new, and desire to secure by Letters Patent, is—

1. In a shoe, the combination, with the button-fly, of an overlying piece attached to the fly with its edge overlapping and covering the inner ends of the button-holes, as and for the purpose specified.

65 2. In a shoe, the combination, with the button-fly, of an overlying piece attached to the fly with its edge overlapping the inner ends of the button-holes, a series of pocket-holes being formed in uniting the parts, whereby a portion of each button-hole is covered, as 70 75 specified.

In witness whereof I have hereunto signed my name in the presence of two subscribing witnesses.

WILLIAM H. WOOD.

Witnesses:

R. F. OSGOOD,
P. A. COSTICH.
